US00D712081S

(12) **United States Design Patent**
Murata et al.

(10) **Patent No.:** **US D712,081 S**
(45) **Date of Patent:** **** Aug. 26, 2014**

(54) **LIGHTING FIXTURE**

(71) Applicant: **Toshiba Lighting & Technology Corporation**, Kanagawa (JP)

(72) Inventors: **Kazuyuki Murata**, Tokyo (JP);
Akimichi Takahashi, Yokosuka (JP);
Jun Ooshima, Yokosuka (JP); **Yasuhiro Sano**, Yokosuka (JP)

(73) Assignee: **Toshiba Lighting & Technology Corporation**, Kanagawa (JP)

(**) Term: **14 Years**

(21) Appl. No.: **29/460,037**

(22) Filed: **Jul. 8, 2013**

(30) **Foreign Application Priority Data**

(57) **CLAIM**

The ornamental design for a lighting fixture, as shown and described.

DESCRIPTION

FIG. 1 is a perspective view of a lighting fixture showing our new design;

FIG. 2 is a front view thereof, the rear view being a mirror image of the front view;

FIG. 3 is a right side view thereof, the left side view being a mirror image of the right side view;

FIG. 4 is a top view thereof; and,

FIG. 5 is a bottom view thereof.

The broken lines in the drawings illustrate portions of the lighting fixture which form no part of the claimed design.

1 Claim, 3 Drawing Sheets
